PANELED BUILDING WALL CONSTRUCTION

John Lintott, Watford, England, assignor to Maycrete Limited, London, England, a company of Great Britain

Application April 20, 1953, Serial No. 349,629

Claims priority, application Great Britain April 22, 1952

5 Claims. (Cl. 20—4)

This invention relates to a building construction. More particularly it is concerned with that type of building which is built up of so-called prefabricated units.

The main object of the present invention is to provide an improved design of wall panel for use in the construction of exterior or party walls of a prefabricated building.

A further object of the invention is to provide an improved method of erection of prefabricated buildings or units having a cavity wall, which are capable of being erected by the use of relatively unskilled labour, the only requirement being a concrete base or other foundation to which the building is anchored.

According to the present invention a panel for use in the erection of walls of prefabricated buildings comprises a frame work of timbering, to which is secured facing sheets of suitable material, e. g. asbestos or fibre board, the composite panel so formed having a reinforcement along two opposite edges of metal strip, which metal strips are respectively provided with interlocking components to enable adjacent panels, when erected, to be connected one to the other.

In a preferred construction the metal reinforcing strip consists of angle section arranged with the flange extending inwardly of the panel and so that the web provides the abutting face between adjacent panels along their vertical sides. One of the reinforcing angle strips may be provided with a lock flange along its outer edge adapted to engage a slot cut in the timbering of the frame of the adjacent panel.

Satisfactory results have been obtained by the use of L-section strip, the web of which is slightly less in width than the total cross-section of the frame of the panel and which is so arranged that the flange, when the panel is erected to form part of a wall, lies on the inside. The interlocking components are conveniently male and female, e. g. studs and slots arranged at spaced intervals from end to end of the strip. The connecting studs may consist of metal tongues projecting in a plane at right angles to the web of the metal angle for engagement with V-shaped slots cut in the web of the opposite angle of the adjacent panel so that when the panels are assembled, the stud, by reason of the tapering sides of the V-shaped slot, automatically centres the panel.

According to a further feature of the invention the wall of a prefabricated building is built up of upper and lower metal channels which extend horizontally and are arranged to face towards one another, the lower channel being anchored, such as by means of rag bolts set into a concrete base, and between which channels are located cavity panels provided along their vertical edges with metal strip having interlocking means. The panels may be located in the base channel or channels by extending the timber styles of the wall panels at their lower ends so as to project beyond the lower edge of the panel and into the bottom of the base channel. At their upper ends the panels fit inside the flanges of the channel.

2

When the panels are in position they may be secured to the base channel by means of screw pins or the like inserted through holes formed in the interior flange of the channel, which pins penetrate the timbering along the bottom edge of the panel.

5 A metal weather strip may be secured along the lower edges of the wall panels, this strip preferably being formed with an offset flange so that it overlies the joint line between the channel and the panel. The weather strip may 10 be secured between the outer sheet of the panel and the timber framing.

The invention is illustrated in the accompanying drawings in which Figure 1 is a view in elevation of a panel unit in accordance with the invention. Figure 2 is a perspective view showing metal strip used to form the reinforcement along two opposite edges of a panel in accordance with the invention, and the interlocking components thereof. Figure 3 is a part horizontal section showing two adjacent panels when interlocked and illustrating the 20 panel construction along two vertical opposite edges. Figure 4 is a similar section illustrating the method of forming a corner joint between two walls built up of panels in accordance with this invention. Figure 5 is a vertical section showing a single panel and the upper reinforcing metal strip and the further reinforcement secured by the base channel of erection of a wall.

Referring to the drawings, the prefabricated wall panel essentially comprises a frame work of timber indicated generally at A (Figure 5), facing sheets B and a reinforcement along two opposite edges provided by metal strips.

In the embodiment shown which illustrates the construction of a rectangular panel, this is built up of upper and lower wood fillets 1 and 2, joined to one another by vertical fillets or styles 3 and 4.

35 Each panel along its vertical sides is provided with metal reinforcements, the metal strip being of such construction that it extends over at least one face and a side edge of the panel in order to give rigidity and to provide an anchorage for interlocking components, by which adjacent panels are attached one to the other. These requirements are conveniently obtained by use of L-section strip so as to provide a continuous metal facing over the said face and edge, i. e. the abutting side edges of the panels and their outer faces. Channel strip may be used as an alternative.

40 In addition to the vertical sides, I preferably also provide metal reinforcement along the horizontal sides. In this case the metal reinforcement along the upper edge consists of channel section strip and is united thereto to form an integral part of the panel structure. Along the bottom horizontal edge, the metal reinforcement is obtained by a separate channel section which is laid down as part of the foundation but is secured to and forms a 45 part of the panel or panels when erected. Transverse tie members are provided at 13'.

45 As can be seen from Figures 2 and 3, the L-strip is so arranged that the wide limb 11 is arranged at the sides with the narrow limb or flange 12 on the outer face. It 50 will be observed also that the limb 11 does not extend over the entire width of the panel measured from front to rear and is less than the width of the wood fillets 3 and 4.

55 The metal strip along one of the vertical edges of each panel is formed with an additional vertical flange 11' which is entered into a slot 14 cut in the opposite edge of the wood fillet of an adjacent panel.

60 Adjacent pairs of panels are connected one to the other by interlocking components which are respectively male and female. As shown in Figure 2, a metal tongue 65 piece 16 is provided on the limb 11 of the strip having the locking flange 11' for engagement with a slot 17 in the

metal reinforcement strip 13 of the opposite side edge of the adjoining panel.

The size of the slot 17 measured from top to bottom is slightly greater than the vertical edge 18 of the tongue 16, and is tapered in a downwards direction so that the width of the slot at the bottom as at 19 is the same as that of the tongue 16, so that when the panels are assembled, the stud, by reason of the tapering sides of the V-shaped slot, will automatically centre the panel as it is dropped into position.

The connecting studs and slots of which there may be two or more are arranged at spaced intervals depending on the size of the panel.

It will be seen that when the panels are erected and the two L-section strips are drawn together back to back, not only is a tight joint made but together with the vertical flange 11', there is produced an almost H-section which is a very strong load bearing unit. The tongue and groove effect of the flange 11' also acts as a weather proof barrier at the vertical joint between adjacent panels.

The facing sheets may be formed of composition insulation board, asbestos sheeting, or other suitable material, and preferably each panel on the inside is formed with a sheet 20 of insulation board or any other type of internal wall lining, and on the outside with a sheet 21 of asbestos, or other material of a heat-resistant character. 28 is a layer of glass wool. The facing sheets are fixed to the transverse members 13'.

The composite building unit of this invention thus eliminates a separate metal frame, in which wall panels normally have to be fixed, with the result that quicker assembly is possible and the framework becomes an integral part of the panel.

The reinforcing metal channel strips, indicated at 22, along the upper horizontal edges of the panels are provided with flanges 23 of a depth preferably to coincide with the thickness of the wood fillet 1. Along the lower edges, the channels indicated at 24, instead of embracing the fillet 2 and inner and outer facing boards 20 and 21, are used to provide a damp course. As can be seen from Figure 5 the wood fillet 2 when the panel is in position rests on the channel 24 so as to enclose an interior air space 25 functioning as the damp course and one of the flanges, preferably the interior flange 26, is formed with an extension 26' to which the fillet 2 is secured by wood screws 27 in the course of erection.

It will be obvious from the foregoing description that the erection of a wall or building from panels constructed in accordance with this invention is a simple procedure and can be carried out by more or less unskilled labour, since, in the preferred construction, the vertical dimension of each panel is such that it extends from the ground to ceiling level so that all the operative has to do is to drop the panel into position on a (usually concrete) foundation indicated at C in Figure 5.

The concrete foundation C may be provided with prepared positions to receive the panels, such as by setting a number of rag bolts indicated at 30 into the concrete, e. g. two or more in accordance with the width of the panel, correspondingly positioned holes 31 being formed in the web of the bottom edge channel to which the panel is secured by fixing nuts 32.

Similar fixing bolts provided with nuts 33 are provided at intervals in the channels extending along the upper edges for attachment to an eave panel indicated at 34.

In practice, the bottom channels initially do not form part of the complete panel and after the concrete foundation C has been laid down together with the rag bolts 30, the channel is bolted down by the fixing nuts 32, when 70 the panel is lowered by the operator on to the channel and subsequently secured from the interior by wood screws 27. As an additional means of locating the panels in the base channel the fillets 3 and 4 forming the styles may be extended at their lower ends as indicated at 3', 75

4' to project beyond the horizontal fillets 2 and extend into the bottom of the base channel.

As a protection against the weather, a metal weather strip 40 may be provided, this strip being secured between the wood fillet 2 and the facing sheet 21 and having an offset flange so that it overlies the joint line between the base channel 24 and the panel. It will be appreciated that although the bottom channel 24 serves as a damp course, a layer of felt or a mastic jointing indicated at 10 24' may be provided to preserve the metal and prevent entry of moisture.

The roof is secured by bolting to the upper channels within which the wall panels are located and in one construction the roof is supported by roof trusses spaced 15 apart from one another by tubular purlins to which corrugated roof sheeting is secured in the normal manner. The ceiling may be provided by ceiling panels made from an insulation board attached to a timber frame.

At a corner where two wall structures join one another, 20 I made use of two vertical timbers 40', 41, one of which timbers 40' is provided with a metal reinforcing strip 11 having tongues to engage slots 17 in the reinforcing strip of the outer panel of one wall structure. The second timber 41 is preferably of slightly greater width and arranged to project beyond the timber 40' to extend a distance sufficient to accommodate the flange 11' of the outer panel of the other wall structure. The fillet 41 is provided with a complementary reinforcing strip 13.

I claim:

1. A building panel adapted for use in combination with similar panels to form a wall, said panel comprising a rectangular body having edge surfaces and face surfaces; a first metal strip of substantially L-shaped cross-section secured to said body along one edge thereof, said 35 one edge having a slot formed therein; a second metal strip of substantially L-shaped cross-section secured to said panel along an opposite edge thereof, each of the L-shaped strips having one of its legs extending partly over a face surface and having its other leg extending partly over a portion of its associated edge surface, said second L-shaped strip having a flange adapted to be received in the slot of an adjacent panel corresponding to said slot in said one edge; and interlocking means for 40 interlocking adjacent panels, said interlocking means comprising a male element on one of said metal strips and a female element on the other of said metal strips, said elements being engageable with complementary elements on the edges of adjacent panels by insertion of the male element into the female element and interlocking said elements by vertical adjustment of one of the panels.

2. A construction as set forth in claim 1 in which said interlocking means comprises a hook shaped tongue projecting from one of said metal strips and a tapered slot in the other of said strips.

3. A construction as set forth in claim 2 in which said hook shaped tongue opens downwardly and in which said tapered slot tapers downwardly.

4. A construction as set forth in claim 3 in which said hook shaped tongue forms a part of said second metal strip and in which said downwardly tapering slot is formed in said first metal strip.

5. A construction as set forth in claim 4 in which each of said other legs of said metal strips are disposed flatly against the corresponding edges of said body and in which there is a recess in that edge over which said first metal strip extends adjacent said downwardly tapering slot so as to receive said hook shaped tongue.
